CLAIM

The ornamental design for an inner cover of a food jar, as shown and described.

DESCRIPTION

FIG. 1 is a top, front, right perspective view of an inner cover of a food jar, showing my design.

FIG. 2 is a bottom, front, right perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view taken in the direction of line 9-9 in FIG. 7.

The broken lines in FIG. 7 denote cross-sectional cut line and form no part of the claimed design. All other broken lines depict portions of the inner cover of a food jar that form no part of the claimed design.
